CRUSHING MACHINE

Oscar C. Gruender, Milwaukee, Wis., assignor to
Nordberg Manufacturing Co., Milwaukee, Wis.,
a corporation of Wisconsin

Application September 25, 1933, Serial No. 690,790

4 Claims. (Cl. 83—10)

My invention relates to an improvement in crushing equipment and has for one purpose the provision of improved means for holding supporting and adjusting the bowl liner of a gyratory crusher. Another object is the provision of improved means for protecting the bowl supporting and liner supporting means from dust. Other objects will appear from time to time in the course of the specifications and claims.

I illustrate my invention more or less diagrammatically in the accompanying drawings, wherein—

Figure 1 is an axial vertical section;

Fig. 2 is a plan view of the bowl structure;

Fig. 3 is a section on the line 3—3 of Figure 2; and

Fig. 4 is a section on the line 4—4 of Figure 1.

Like parts are indicated by like symbols throughout.

Referring to the drawings, A generally indicates a fixed circumferential main frame which may be supported upon any suitable base. It is provided with a circumferential outwardly projecting upper flange A¹ upon which is tiltably mounted the ring A², the flange and ring being formed to interpenetrate as shown in Figure 1. A³ are springs tending normally to hold the ring fixed in relation to the flange by means of a spring abutment A⁴ and the members A⁵ which maintain the springs under pressure.

B generally indicates the bowl structure. It includes an upwardly and inwardly inclined wall B¹, an upwardly and outwardly inclined wall B² and a generally cylindrical outer wall B³ herein shown as screwthreaded as at B⁴ to mesh with the screwthreaded ring A². Any suitable means may be employed for imparting rotation to the member B in relation to the ring A², whereby its vertical adjustment is obtained. It will be understood that such adjusting means, however, are not of themselves part of the present invention and will not be described in great detail. B⁵ is any suitable housing member herein shown as resting upon the top of the ring A² and extending upwardly and inwardly as at B⁶, and housing the space above the area of screwthreaded contact with the members A² and B³. It is provided with apertures B¹⁰ through which pass headed screw or bolts B⁷ whereby the bowl may be drawn upwardly in order to lock it at any desired adjustment. It will be noted that the lower portion of the screw B⁷ is positioned within the space defined by the walls B¹, B², and B³. The wall B² is provided with apertures B⁸ having removable cover plates B⁹ the purpose for which will later appear. The lower wall B¹ is provided with a plurality of apertures B¹⁰.

C indicates a bowl liner for the bowl B which liner is provided with hook shaped flanges C¹ adapted to penetrate through the apertures B¹⁰.

and to be engaged by the generally U-shaped bolts C² which pass through abutment blocks or bolt plate C³ mounted on ribs C⁴ herein shown as formed integrally with the bowl structure B and as connecting the walls B¹, B². C⁵ are nuts for the two arms of the bolt C², and C⁶ indicate washers therefor. Compressed between the washers and the bolt plate C³ are springs C⁷. C⁸ indicates any suitable lock washer or locking member adapted to rest on the washers C⁶ and to prevent rotation of the nuts C⁵. It will be observed that the apertures B⁸ and the cover plates B⁹ overlie the U-bolts C² and the attaching means therefor, thus providing means of ready access thereto. The rib C⁹ on the lock washer C⁸ extends up close to the cover plate B⁹ which serves to hold the lock washer in place.

D indicates the bearing sleeve preferably formed integral with the frame A and connected thereto in any suitable manner by ribs or the like. It is provided with an upward enlargement D¹. Rotatable within the cylindrical bore of the sleeve D is a sleeve D² provided with an eccentric tapered bore D³. It carries at the top the drive gear D⁴ which rotates within the space D¹. The gear D⁴ is in mesh with the pinion D⁵ on the drive shaft D⁶. D⁷ is a cover plate carrying the spherical bearing member D⁸.

E indicates a crusher shaft intermediate the aperture D³. Associated therewith is the crusher head E¹ which is provided with a spherical bearing surface E² adapted to conform to and rest upon the spherical bearing member D⁸. Any suitable means may be employed for preventing the access of dust to the opposed spherical bearing surfaces. I illustrate for example the spherical surfaced outer members E³ E⁴ formed concentric with the main surface E², and an opposed wiping means therefor, E⁵, upwardly thrust thereagainst as by the springs E⁶.

Mounted upon the upwardly tapered surface of the head E¹ is the crushing mantle G. Opposed to the upper edge thereof is the locking ring or nut G¹. G² generally indicates a securing member secured as by the screws G³ to the top of the head E¹. It is outwardly screwthreaded as at G⁴ to mesh with the nut G¹. It will be understood that in response to movement or crawl of the mantle G, which may be of manganese steel or the like, the nut G¹ tends to tighten itself upon the securing member G², thereby maintaining a downward pressure against the upper edge of the mantle G which automatically effects its firm seating upon the head. G⁵ indicates a cover plate secured to the ring G¹ as by the screws G⁶. It overlies also the heads of the screws G³ and serves as a species of generally horizontal feed plate for the top of the head. It also has a central upward extension or sleeve G⁷ which surrounds a corresponding upward 60

extension of the member G² in relation to which it may freely rotate when the nut G¹ rotates in relation to the member G². I may employ, however, a wiping connection G³ to prevent the access 5 of dust.

Secured to the top of the member G² is a feed assembly having a central portion generally indicated as H. It may be held in position for example by the headed screw H¹. Outwardly projecting therefrom are the ribs H² upon which any suitable inwardly tapered hopper structure H³ may be mounted with removable wear taking plates H⁴. The proportion and location of the parts is such that any material delivered to 10 the hopper H² will be directed thereby to the top of the member G⁵ whence it will find its way into the crushing cavity defined by the opposed liner C and head mantle G. H⁵ indicates a feed receiving plate having a central portion H⁶ removably secured as by the screw H⁷ to the member H.

It will be understood that rotation of the shaft D⁶ rotates the concentrically apertured sleeve D² and thereby imparts gyration to the shaft E and the head E¹. The effect of the spherical support for the head is to impart to it a movement as if it were being gyrated about a fixed center somewhat above the top of the head, the center about which the spherical bearing surface E² is described. This gyration effects the crushing movement of the head. Feed may be delivered to the top of the plate portions H⁵, H⁶ by any suitable means, for example, through the spout J. It escapes over the edge of the plate H⁵, drops into 30 the hopper H³, thence drops to the member G⁵ and flows over the edge of the head into the crushing cavity between the bowl liner C and the mantle G where it is crushed, escaping downwardly by gravity through the crushing zone.

40 In removing or adjusting the bowl liner C the operator removes the cover plates B⁹. He can then lift off the lock washers or locking members C⁸ of which there is one for each pair of nuts C⁵. With these lock washers or members removed the 45 nuts can be released and the U-bolt assembly can then be lifted from the hook shaped lugs C¹. It is advantageous to have the securing means entirely housed within the bowl assembly, protected from dust and grit. The shield B⁵ closes 50 whatever apertures there may be in the top of the bowl assembly B and protects the screw-threaded connection between the bowl and the ring A². B¹⁵ is any suitable dust-proof closure to protect the lower side of the screwthreaded 55 engagement of the opposed parts.

It will be realized that whereas I have described and shown a practical and operative device, nevertheless, many changes might be made in the size, shape, number and disposition of parts without departing from the spirit of my invention. I therefore wish my description and drawings 60 to be taken as in a broad sense illustrative and diagrammatic rather than as limiting me to my specific showing.

65 I claim:

1. In a gyratory crusher which includes a crushing head and means for gyrating it, a main frame, a hollow bowl liner support adjustably positioned on the main frame, said support including an outer and generally cylindrical wall, an inner and lower conic wall extending upwardly and inwardly from the lower edge of the cylindrical wall, and an upper conic wall extending

downwardly and inwardly from the upper portion of the cylindrical wall, the two conic walls being joined to each other at their opposed edges, and a bowl liner secured to the lower conic wall, said bowl liner having securing lugs extending 5 from the face thereof opposite the crushing face, and penetrating the interior of the support, the support being provided with apertures aligned therewith, and securing means for said lugs positioned within the hollow of said support, including bolts extending upwardly from said lugs in the direction of the upper conic wall, said upper conic wall being apertured to align with said bolts, readily removable cover plates for said apertures, and lock nut means for said bolts, said plates 10 when in position, cooperating with the lock nut means to prevent displacement of said lock nut means.

2. In securing means for securing two members together, a lug on one of said members, the other member being apertured to permit the passage of the lug therethrough, a housing associated with the apertured member, said housing having an access opening, rotatable securing means for said lug, positioned within said housing and aligned with said opening, a cover member for 15 said opening and means for securing it in place, and means cooperating with said cover member, when in place, to prevent rotation of said rotatable securing means.

3. In securing means for securing two members together, a lug on one of said members, the other member being apertured to permit the passage of the lug therethrough, a housing associated with the apertured member, said housing having an access opening, rotatable securing means for said lug, positioned within said housing and aligned with said opening, a cover member for 25 said opening and means for securing it in place, and a locking member cooperating with said cover member when in place, to prevent rotation of said rotatable securing means.

4. In a gyratory crusher which includes a 30

crushing head and means for gyrating it, a main frame, a hollow bowl liner support positioned on the main frame, said support including an outer and generally cylindrical wall, an inner and lower conic wall extending upwardly and inwardly from the lower edge of the outer cylindrical wall, and an upper conic wall extending downwardly and inwardly from the upper portion of the cylindrical wall, the two conic walls joining each other at their opposed inner edges, and a bowl 35 liner secured to the lower conic wall, said liner including hook-shaped lugs extending from the face thereof opposite to its crushing face, the lower face of the support being provided with apertures through which said hook-shaped lugs 40 penetrate, and securing means for said lugs positioned within the interior of said support, including U-shaped bolts adapted each to engage one of said hook-shaped lugs, nuts on the arms of said bolts, unitary means aligned with apertures 45 in the upper conic wall for simultaneously preventing the undesired rotation of the nuts of the two arms of the individual U-shaped bolts, and covers for such apertures in the upper wall, engaging said unitary means and holding them in 50 operative position.

OSCAR C. GRUENDER.
